UNITED STATES PATENT OFFICE

2,555,797

TROLLEY POLE ARRESTER

Frederick W. Krause, Carmichaels, Pa.

Application March 8, 1948, Serial No. 13,561

2 Claims. (Cl. 191—68)

1

The present invention relates to new and useful improvements in trolley poles and more particularly to means for arresting the upward swinging movement of the pole should the pole accidentally leave the trolley line.

The invention is designed particularly for use with electric locomotives of mine cars and similar industrial equipment and the invention has for its primary object to arrest the sudden upward movement of the pole should the same accidentally leave the wire to prevent the pole striking the roof, steel beams or other overhead structure of the mine and which frequently results in breakage or other damage to the pole.

More specifically, the invention embodies the provision of a dash-pot mechanism including a piston to which the base of the pole is attached to retard the sudden upward movement of the pole and thus enable the operator to reach the pole for again placing the same on the line before any damage results thereto.

A further object of the invention is to provide dash-pot arresting means for the pole and including a hydraulic cylinder with piston working therein and providing valves in the piston to control the sudden movement thereof.

A still further object is to provide a device of this character of simple and practical construction, which is efficient and reliable in operation, relatively inexpensive to manufacture and install in operative position in a mine locomotive and which otherwise is well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view of a mine locomotive equipped with the present invention and with parts broken away and shown in section;

Figure 2 is an enlarged top plan view of the pivotal supporting base for the pole;

Figure 3 is a transverse sectional view taken substantially on a line 3—3 of Figure 2;

Figure 4 is an enlarged vertical sectional view of the dash-pot;

Figure 5 is an enlarged transverse sectional view taken substantially on a line 5—5 of Figure 4;

Figure 6 is an enlarged fragmentary sectional view of the spring actuated check valve, and

2

Figure 7 is a sectional view taken on a line 7—7 of Figure 6.

Referring now to the drawings in detail wherein for the purpose of illustration I have disclosed a preferred embodiment of the invention, the numeral 5 designates a conventional type or mine locomotive having an opening 6 in the top 7 thereof and in which a cylinder 8 is secured by means of a flange or collar 9 suitably secured to the cylinder in engagement with the underside of the top 7 and with a pole supporting base 10 resting on top of the locomotive and to which the top of the cylinder 8 is threaded.

One end of the base 10 is provided with a pair of spaced apart upstanding apertured ears 11 having a pin 12 positioned therein and on which the socket 13 for receiving the lower end of a trolley pole 14 is pivoted. The socket 13 is formed with an arm 15 which overlies an opening 16 in base 10 and to which the upper end of a piston rod 17 is attached.

The piston rod extends downwardly through the opening 16 into the cylinder 8 and has a piston 18 secured to its lower end, the piston being composed of upper and lower plates 19 and 20 with a flexible washer such as leather or the like 21 held therebetween.

Light oil or other suitable liquid is placed in the cylinder 8 and the top of the cylinder is sealed by a flexible substantially conical shaped cover 22 secured at its lower central portion to the piston rod 17 by a clamp 23 and having its upper edges secured in the top of cylinder 8 by retaining rings 24.

A pair of openings or passages 25 extend through piston 18 and are closed by ball checks 26 retained in cages 27 by transverse pins 28, the cages being formed at the underside of the lower plate 20.

A third passage 29 is provided in piston 18 controlled by a valve 30 in the lower end of a neck 31 extending downwardly from lower plate 20, the valve having a stem 32 slidable in a spider 33 in the neck and against which a coil spring 34 is held for opening the valve.

A bleed port 35 is also provided in piston 18.

In order to prevent dirt entering the opening 16 of base 10 I provide a rectangular shaped recess 36 in the top of base 10 in which a cover plate 37 is freely slidable to at all times cover opening 16 and through which piston rod 17 extends to slide the cover plate forwardly and rearwardly by the raising and lowering movement of pole 14.

A coil spring 38 in cylinder 8 above piston 18

forces the piston downwardly to hold the pole 14 in its raised position for travelling along power line 39.

In the operation of the device, the spring 38 maintains a constant downward force on piston 18 and piston rod 17 to hold the pole 14 upwardly to travel on power line 39. In normal operating position of pole 14 of electric locomotive 5, valves 26 and 30 are open and when pole 14 jumps from line 39 spring 38 will lower piston 18 and raise pole 14. The initial sudden downward movement of piston 18 will close valves 26 and 30 to retard movement of the piston, the bleed port 35 allowing fluid compressed in the bottom of cylinder 8 to pass slowly above the piston so that the raising movement of pole 14 is slowed to a speed which will afford sufficient time for the motorman to reach the pole before the same strikes the roof of the mine and replace the pole on the line 39.

The manual lowering movement of the pole will quickly open valves 26 and 30 to prevent compression of fluid in the upper portion of the cylinder and thus avoid retarding of the lowering of the pole.

In order to maintain the parts of the piston 18 in a fixed position to align the several ports therein, I provide an aligning pin 40 which threads into lower plate 20 and extends upwardly through openings (not shown) in the leather washer 20a and upper plate 19.

Having described the invention what is claimed as new is:

1. A trolley pole snubber comprising a cylinder, means securing the cylinder in a fixed recessed position in the top of a car and including a pole

base secured to the cylinder on top of the cap, a pole pivoted to the base and including an arm overlying the base, a valved piston working in the cylinder, a piston rod connecting the piston to the arm, spring means in the cylinder and engaging the piston to raise the pole, said base having an enlarged opening for receiving the piston rod, and a sealing plate for the opening slidably receiving the piston rod and movable with the piston rod during its tilting movement when the pole is raised.

2. A trolley pole snubber comprising a vertical cylinder, means securing the cylinder in a fixed recessed position in the top of a car and including a pole base on the top of the cylinder and having an opening, a pole pivoted to the base and including an arm overlying the opening in the base, a valved piston working in the cylinder, a piston rod connected to the piston and extending upwardly through the opening with free lateral movement of the rod therein, means connecting the upper end of the rod to the arm, spring means in the cylinder engaging the piston to raise the pole, and a flexible seal in the top of the cylinder for the rod.

FREDERICK W. KRAUSE.
